US0D1018124S

(12) **United States Design Patent** (10) **Patent No.:** **US D1,018,124 S**
(45) **Date of Patent:** **** Mar. 19, 2024**

(54) **BED LEVER**

(71) Applicant: **Zhejiang Kangbeide Smart Furnishings Co., Ltd.**, Zhejiang (CN)

(72) Inventor: **Yuelian Xu**, Zhejiang (CN)

(73) Assignee: **Zhejiang Kangbeide Smart Furnishings Co., Ltd.**, Zhejiang (CN)

(**) Term: **15 Years**

(21) Appl. No.: **29/821,269**

(22) Filed: **Dec. 29, 2021**

(51) LOC (14) Cl. **23-08**

(52) U.S. Cl.

USPC **D6/549**

(57) **CLAIM**

The ornamental design for a bed lever, as shown and described.

DESCRIPTION

FIG. 1 is a perspective view of a bed lever showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the bed lever in FIGS. 1-7 forms no part of the claimed design.

1 Claim, 5 Drawing Sheets
